UNITED STATES PATENT OFFICE.

FRANCES H. MORRISON, OF TAMPICO, MEXICO, ASSIGNOR OF ONE-HALF TO BENJAMIN E. PARRISH, OF EL LIMON, SAN LUIS POTOSI, MEXICO.

BRASSIÈRE.

Application filed October 21, 1927. Serial No. 227,709.

This invention is an improvement in brassières, and more particularly in brassières of the type designed to afford an efficient support with a minimum of discomfort.

With modern women's clothing, it is desirable that the lines of the bust be natural, particularly with garments of the clinging type. Any garment in the way of a support or an accessory to the toilet, must be of a nature such that it is invisible, and not evident to the sense of feeling, to meet the requirements of women of taste.

It is desirable also that any supporting garment of this type shall be of such a character that there is no possibility of displacement of the parts while the garment is being worn, and that any parts thereof which are liable to be visible at any time, should harmonize with the remainder of the costume and the natural figure.

One of the primary objects of the present invention is the provision of a garment of the character in question, particularly designed to hold the bust in its natural position, without any tendency of the parts to slip away from the garment, either above or below, and wherein the natural division between the breasts is maintained.

Another object is the provision of a lightweight garment capable of being easily laundered, providing for efficient support with the maximum exposure of the skin, thus to insure coolness.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a perspective view showing the improved garment in use and looking at the front.

Fig. 2 is an enlarged perspective looking from the rear.

Fig. 3 is a perspective view of a part of the alternate construction.

In the present embodiment of the inven-

tion, a plurality of individual supports 1, in the nature of disks or caps, is provided of suitable material, which are preferably shaped to fit the breasts of the wearer, and to preserve the natural appearance thereof when in place.

In the present instance, each support is composed of a circular piece having four darts arranged at angular intervals of 90°, which shapes the piece to provide for a cap in substantially the shape of a segment of a sphere. The peripheral edges of the pieces are hemmed, as shown at 2, to provide for a finish at the perimeter of the support.

The caps are connected to a belt or girdle strap 3, which is relatively wide, and of a length to encircle the body of the wearer just below the breasts. The ends of the strap are at the front, between the supports, and any suitable connecting means, indicated at 4, is provided for connecting said ends.

Another strap 5 is arranged between the supports, one end of the strap being permanently connected to one of the supports at the end of the horizontal diameter thereof, while the other end of the strap is detachably connected with the other support at a like point, the connection being indicated at 6.

A third strap 7 is also provided for connecting the individual supports 1, the said strap being below the strap 5, and midway between the said strap and the belt 3. This strap 7 is permanently connected with the support to which the strap 5 is permanently connected and detachably connected with the other support, the detachable connection being indicated at 8.

The garment includes also straps 9, which go over the shoulders of the wearer. Each strap 9 is permanently connected at one end to the top of the adjacent support 1, as indicated at 10, and at the other end to the belt 3, as indicated at 11.

The belt 3 provides for a support at the bottoms of the individual supports, holding them in close contact with the body, while the straps 9 provide for a support at the tops of the individual supports. The straps 5 and 7, and also the strap 3, provide for support between the individual supports, and other mechanism is provided for retaining the outer or remote sides of the individual

supports in close contact with the body of the wearer.

The straps 9 are connected just above the belt 3 by a strap 12, secured at its ends to the straps 9, and each strap 9 is connected to the adjacent individual support at the rear by a plurality of connections, said connections being at the ends of the strap 12, and diverging from said ends toward the individual supports, as clearly shown in Figure 2. Each of the said connections includes three parts, 13, 14 and 15, having a common connection at 15^a, with the adjacent strap 9 and the end of the strap 12, and having individual connections with the individual supports, indicated at 16, 17 and 18, respectively.

Referring to Figure 1, it will be seen that connections 16 are directly opposite the connections of the ends of the strap 5. The connections 17 are opposite the connections for the ends of the strap 7, and each connection 18 provides a common connection for the strap 15, the belt 3, and the adjacent individual support.

Thus the lower half of the perimeter of each individual support is held in close contact with the body, by a plurality of holding means, while at the same time a minimum area of the body is covered by the holding means, thus providing for coolness and ventilation. There is but little tendency of the breasts to escape above the horizontal diameter, such tendency being pronounced, however, below the horizontal diameter. Substantially the entire upper half of the perimeter of each individual support is left free, thus providing for circulation of air between the supports and the skin, without lessening in any degree the efficiency of the support, so far as concerns restraining the breasts from escape.

Furthermore, the improved brassière may be worn with low-neck and sleeveless gowns, without any part thereof being exposed. Such garments have shoulder straps, which coincide with the straps 9, covering and concealing the same. The topmost supports 5 and 13 are far enough below the arm-pit so that the usual evening garments would not expose them. The belt 3 is of a length to fit about the body just below the point where it reaches its maximum outward curvature above the waist-line, and by this arrangement upward movement of the belt is restrained. The tendency is for the belt to push down rather than upward, so that the brassière is held in its normal position.

At the back the garment is well below the normal low-cut of the back of the evening gown, and there is but little mechanism in the way of harness that is evident to the sense of "feeling", as for instance by the hand of a dancing partner. All of the straps are of non-elastic material, there being no

elastic material of any character used in the 65 improved brassière.

In Fig. 3 a construction is shown capable of a considerable degree of adjustment. The only difference between this construction and that shown in Fig. 2 is that the strap 12^a is 70 sectional, and the sections are provided with interengaging means 20, such as a button on one section and a plurality of button holes on the other. The strap 3^a corresponding to strap 3 of Fig. 2 is divided at the back instead of at the front, and fastening means indicated at 21 is provided for connecting the ends of the divided strap. As shown two buttons are arranged on one section, and sets of button holes on the other for engaging the buttons.

It will be understood that in this arrangement the straps 5 and 7 are permanently connected to the elements 1, the opening for the brassière being at the back instead of at 85 the front.

What is claimed as new is:—

1. A garment of the character specified, including a pair of individual supports, a belt or girdle of a length to encircle the body 90 just below the swell of the bust, the said girdle connected to the individual supports at the lowest parts thereof, a shoulder strap connected with the top of each support and with the girdle at the rear, a plurality of 95 connections between the outer side of the lower part of each support and the adjacent strap, and a connection at the rear between the straps in substantially the line of the plurality of connections.

2. A garment of the character specified, including a pair of individual supports, a belt or girdle of a length to encircle the body just below the swell of the bust, the said girdle connected to the individual supports 100 at the lowest parts thereof, a shoulder strap connected with the top of each support and with the girdle at the rear, a plurality of connections between the outer side of the lower part of each support and the adjacent 105 strap, and a connection at the rear between the straps in substantially the line of the plurality of connections, the plurality of connections having a common connection with the strap and diverging toward the adjacent support.

3. A garment of the character specified, including a pair of individual supports, a belt or girdle of a length to encircle the body just below the swell of the bust, the said 110 girdle connected to the individual supports at the lowest parts thereof, a shoulder strap connected with the top of each support and with the girdle at the rear, a plurality of connections between the outer side of the lower part of each support and the adjacent 115 strap, a connection at the rear between the straps in substantially the line of the

plurality of connections, and a connection between the supports at the front, said connection detachable from one support, and the girdle being adapted to open at the front.

5. 4. A garment of the character specified, including a pair of individual supports, a relatively narrow belt or girdle of a length to encircle the body just below the swell of the bust, the said girdle connected to the individual supports at the lowest parts thereof, a shoulder strap connected with the top of each support and with the girdle at the

rear, a plurality of connections between the outer side of the lower part of each support and the adjacent strap, a connection at the rear between the straps in substantially the line of the plurality of connections, and a plurality of connections between the lower parts of the supports.

Signed at New York city in the county of 20
New York and State of New York this 11th
day of October A. D. 1927.

FRANCES H. MORRISON.
